UNITED STATES PATENT OFFICE.

HENRY P. HOLLAND, OF SAN FRANCISCO, CALIFORNIA.

ORE-CONCENTRATOR.

SPECIFICATION forming part of Letters Patent No. 416,704, dated December 3, 1889.

Application filed September 5, 1887. Serial No. 248,914. (No model.)

To all whom it may concern:

Be it known that I, HENRY P. HOLLAND, of the city and county of San Francisco, State of California, have invented an Improved Ore-Concentrator; and I do hereby declare that the following is a full, clear, and exact description thereof.

My invention relates to an improved machine for concentrating and separating the heavy particles of ore pulp from the lighter and worthless portions called "gangue," and it consists, chiefly, in the employment of a blanket-belt or concentrating-surface, of a peculiar quality or style of manufacture, by which I have been able to obtain especially gratifying results, as will more fully appear in the following specification, in which reference is made to certain drawings, filed herewith, in which—

Figure 1 is a side elevation. Fig. 2 is a plan. Fig. 3 is an end view. Fig. 4 is a transverse section of the endless belt. Fig. 5 is a side view of the endless belt, showing cable and edge piece. Fig. 6 is a bottom view of the endless belt, showing the wire frame. Fig. 7 is a longitudinal central section of the device. Fig. 8 is an enlarged plan view of a portion of the belt, showing the construction thereof.

Before proceeding to minutely describe my invention I will state that the frame which supports and the mechanism which drives my blanket-belt is not materially different from that used with other endless-belt concentrators.

Let A B C represent the three rollers around which my endless belt passes. The roller B is mounted adjustably in bearings in standards D, which can be raised or lowered to increase or diminish the tension on the belt.

The stationary trough or table E, which extends between the two end rollers A C, I incline slightly, so that its lower end will be at A and its upper end at C. This trough is as wide as the machine and its bottom or floor is made of sheet metal—iron or copper preferred—and it may be smooth or corrugated lengthwise. At a short distance from the roller A—say from one to two feet—I make a transverse slot *a* in this floor, which slot communicates with a trough or receptacle *b* underneath the table. This trough inclines

transversely across the machine, and its lower end has a tube *d*, connected with it, which leads down into the tank Q below, as represented at Figs. 1 and 2.

The endless belt F which I use is made of woven or knitted woolen yarn, and is corrugated transversely in the weaving, so that it presents alternate elevations and depressions on either of its sides, as shown in Fig. 5, which elevations and depressions serve as riffles.

With woven belts, constructed either flat in form or with ribs extending from the upper surface thereof, it has been found from practical experience that there is a constant tendency to shrink in use, which is liable in a comparatively short space of time to render the belt incapable of performing its function by closing its pores. It will be readily understood that a concentrating-belt constructed in the manner and of the form hereinabove set forth possesses, in addition to the riffles stated, the benefit of the elasticity of the wool, and also a remedy for its tendency to shrink. It will be further understood that something of the advantages of the rubber belt is gained in addition to the permeability of the knit goods. In order to prepare this blanket to serve as a belt, I bind its edges with canvas, duck, or some equivalent inelastic material *g*, and I secure to each edge a narrow strip *h*, of india-rubber, leather, or other flexible substance that will extend up and rest upon the shallow sides of the trough or table E, thus forming a trough-shaped belt for the pulp to move in. I then secure a flexible wire rope or cord *f* along the under side of each edge, and these two ropes or cords I connect at intervals by cross wires or cables *k*, which form a flexible connection that is sufficiently rigid to preserve the tension and shape of the blanket-belt, and at the same time admits of its passing freely around the rollers.

The lower portion of the endless belt passes through the tank Q in the usual way, and a revolving brush L is mounted in the tank just below the water-level, so as to sweep the surface of the belt as it leaves the water and clean it of all adhering particles, so that they fall into the tank. In addition to this brush, I employ a perforated spray-pipe M, above the belt, just after it leaves the water, so that

a spray or series of water-jets are forced from the perforations against the inner side of the belt with sufficient force to cleanse the interstices of the belt from adhering particles.

5 In operation the pulp from the battery is fed upon the belt near its upper end through a spout P, and a stream of water is also fed upon the belt just behind the spout P. The belt is kept moving steadily in the direction shown by the arrow, so that the pulp and water travel in the same direction on a slight downgrade. During the travel of the belt down the grade the pulp will flow over the ribs of the blanket-belt as if they were riffles and the heavy particles will settle into the depressions between the ribs and either pass into or through the interstices of the belt or become entangled in the fibers of the belt. If the particles are very small, 10 they may pass entirely through the belt and fall upon the platform or table underneath it, in which case the water will carry them down until they pass through slot a and into the trough or receptacle b, and thence through the tube d into the tank Q below. The other particles which lodge on the endless belt or in its interstices will be carried around until they are either washed off into tank Q or brushed off by the brush L. Gangue is 15 discharged from the belt at the lower end of the machine.

In order to catch and save the fine gold which floats on the surface of the water, commonly known as "slimes" or "float-gold," I 20 employ a floating skimmer S, which is constructed as follows and anchored in the trough:

T is a tube having a longitudinal opening in it. This tube is long enough to extend 25 across the endless belt. It has other tubes U, connecting it at right angles with a corresponding parallel tube T', and this latter tube is connected at one end by a flexible tube V, which leads down into a barrel W 30 below the machine. The slotted or open side of the tube T is upstream, so that as the skimmer floats on the surface of the water a thin film of the surface-water will flow into

the slot, and thence pass through the connecting-tubes U into the parallel tube T', and thence down through the tube V into the barrel below.

I do not confine myself to this particular construction of a skimmer, as it can be variously constructed and yet perform the same duty; but the one herein described will serve the purpose. When the fine gold is once collected in the barrel, it can easily be precipitated and recovered. By this means and apparatus I can save the finest particles of 50 metals and sulphurets, as well as the coarse particles.

Having thus described my invention, what I claim, and desire to secure by Letters Patent, is—

1. An improved concentrating-surface consisting of a belt having alternate elevations and depressions woven on either side thereof, as shown.

2. An improved concentrating-surface consisting of a woven or knitted woolen belt having alternate elevations and depressions permanently formed on either side thereof, substantially as shown, and for the purposes set forth.

3. In an ore-concentrator, the combination, with the main frame thereof, and the rollers A, B, and C, of an endless concentrating-belt passing over said rollers and having alternate elevations and depressions woven therein, and a flexible backing for said belt.

4. A concentrating-belt formed of porous or textile material and having alternate elevations and depressions woven therein, an inelastic binding-piece g, secured to the edges of 85 said belt, and a flexible strip h, also secured to the edges of said belt, in combination with a table, to the sides of which the upper portion of said strip h is secured.

In witness whereof I have hereunto set my hand.

HENRY P. HOLLAND.
